Primary Examiner — Christian P. Mclean

(57) **CLAIM**

The ornamental design for a cabinet protection device, as shown and described.

DESCRIPTION

FIG. 1 is a top plan view of a cabinet protection device, showing my new design;

FIG. 2 is a right side perspective view thereof;

FIG. 3 is a front elevation view thereof;

FIG. 4 is a top perspective view thereof;

FIG. 5 is a rear elevation view thereof;

FIG. 6 is a left side perspective view thereof; and,

FIG. 7 is a bottom plan view thereof.

The broken line showing of a cabinet protection device is for the purpose of illustrating portions of the article and forms no part of the claimed design.

1 Claim, 7 Drawing Sheets
